Primary Examiner — Ricky Pham

(74) Attorney, Agent, or Firm — Norton Rose Fulbright
Canada LLP(57) **CLAIM**

We claim the ornamental design for an aircraft credenza, as shown and described.

DESCRIPTION

FIG. 1 is front tridimensional view of an aircraft credenza showing our new design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view of thereof.

Any parts shown in broken lines form no part of the claimed design.
